UNITED STATES PATENT OFFICE.

CHARLES H. ROBBINS, OF GLEASONDALE, MASSACHUSETTS, ASSIGNOR TO C. A. CLAFLIN COMPANY, OF BOSTON, MASSACHUSETTS, A CORPORATION OF MASSACHUSETTS.

APPARATUS FOR DYEING.

1,378,618.

Specification of Letters Patent. Patented May 17, 1921.

Application filed April 28, 1920. Serial No. 377,386.

To all whom it may concern:

Be it known that I, CHARLES H. ROBBINS, a citizen of the United States of America, and a resident of Gleasondale, in the county 5 of Middlesex and Commonwealth of Massachusetts, have invented certain new and useful Improvements in Apparatus for Dyeing, of which the following is a specification.

This invention relates to an apparatus for 10 dyeing and has for its object the production of a mechanism whereby a uniform color to the wool or other material submerged in the dye liquor may be quickly obtained.

The invention consists in an apparatus 15 for pumping the dye liquor from the bottom of the dye vat and through a system of pipes into a revolute spraying device within the vat and positioned above the wool or other material submerged in the dye liquor.

20 The invention further consists in providing a revolute hollow head having a plurality of perforated tubular members radiating therefrom and closed at their outer ends.

25 The invention further consists in providing means whereby these radiating tubular members may be adjusted about their axes.

The invention further consists in providing 30 the revolute head with radiating tubular members the bore at the outer end of each of which is considerably less in diameter than the bore at the inner end.

The invention further consists of certain 35 novel features of construction and arrangement of parts which will be fully understood by reference to the description of the drawings and to the claims to be hereinafter given.

40 For the purpose of illustrating the invention, one preferred form thereof is illustrated in the drawings, this form having been found to give satisfactory and reliable results, although it is to be understood that the various instrumentalities of which the 45 invention consists can be variously arranged and organized and the invention is not limited to the precise arrangement and organization of these instrumentalities as herein shown and described, except as required by the scope of the appended claims.

In the drawings:

Figure 1 represents a section of a dyeing vat showing in elevation an apparatus coact-

ing therewith and embodying the principles of the present invention. 55

Fig. 2 represents a plan of the vat with the spraying device contained therein.

Fig. 3 represents a vertical section of a portion of the spraying device, drawn to an enlarged scale, and 60

Fig. 4 represents a section of the same on line 4, 4, on Fig. 3.

Similar characters indicate like parts throughout the several figures of the drawings. 65

In the drawings, 10 is a flooring or other support having superimposed thereon blocks 11 on which is positioned a dye vat 12 having the usual perforated false bottom 13 for the support of the wool or other material 70 which it is desired to dye.

From the lower end of the vat 12 extends an outlet pipe 14 to a T 15 supported upon a foundation 16.

From one branch of the T 15 extends a 75 pipe 17 having a valve 18 therein. From another branch of said T 15 extends a pipe 19 communicating with a centrifugal pump 20 having an outlet branch 21 communicating with a vertical pipe 22.

At the upper end of the vertical pipe 22 is a swing joint 23 having a horizontal pipe 24 extending therefrom, said horizontal pipe 24 having a downward branch 25 on the lower end of which is mounted the revolute 85 spraying device 26.

The horizontal pipe 24 has secured thereto, a collar 27 from which extends a cable or cord 28 passing over a sheave or block 29. By means of this cord 28 the horizontal pipe 90 24 with the spraying device 26 on its branch 25 may be raised into the position shown in dotted lines in Fig. 1 of the drawings thereby giving free access to the vat 12.

The pump 21 is actuated by means of a 95 shaft 30 driven by a steam turbine 31 to which steam may be admitted through the pipe 32, said steam being exhausted through the pipe 33.

The pump 21 and the steam turbine or other motor 31 may be of any usual construction.

When the pump is in operation the dye liquor within the vat 12 is pumped therefrom through the pipes 19, 22, 24 and 25 105 into the spraying device 26 and therefrom

onto the material submerged in the liquor within said vat 12.

When the dye liquor is being thus circulated by means of the pump 20, the valve 18 5 is closed.

When it is desired to draw off the dye liquor from the vat 12 the valve 34 in the steam pipe 32 is closed and the valve 18 is opened thus permitting the liquor in the vat 10 to flow through the pipe 17 to any suitable receptacle therefor.

The lower end of the branch pipe 25 is provided with an annular flange 35 on which is positioned a grooved plate 36 having a 15 plurality of balls 37 in the groove thereof and upon these balls is positioned another annular groove plate 38.

On the upper surface of the plate 38 rests the cap 39 of the revoluble hollow head 40.

20 This head 40 has a plurality of inwardly extending hubs 41 into each of which is screwed a tubular member 42.

Each of these members 42 is provided with a flat-sided portion 43 by which said 25 tubular member 42 may be moved about its axis.

To the outer end of each tubular member 42 is threaded a union 44 having extending outwardly therefrom a tubular member 45 30 the bore of which is considerably less in diameter than the bore of the member 42.

The outer end of each tubular member 45 is closed by a cap 46.

Each of the tubular members 42 and 45 35 is provided with a plurality of perforations 47 through which the liquor pumped into the interior of the head 40 may be forced outwardly upon the upper surface of the liquor within the vat 12.

40 The head 40 is freely revoluble about the axis of the branch pipe 25 and the openings 47 in the tubular members 42, 45 are located at an angle to the upper surface 48 of the liquor within the vat 12 as indicated 45 in dotted lines in Fig. 4 of the drawings.

As the liquor is ejected through these perforations 47 and strikes the upper surface 48 of the liquor within the vat 12, the head 40 will be caused to rotate about the axis 50 of the branch pipe 25 on the lower end of which said head 40 is mounted.

The plurality of streams of liquor ejected through the said openings 47 in the various tubular members 42 and 45 will effect the 55 rotation of the head 40 and by varying the angle of these discharge openings 47 relatively to the upper surface of the liquor within the vat 12, the speed of rotation of the head 40 may be varied as desired.

60 As the various streams of liquor passing through the system and ejected through the openings 47 comes into contact with the dye liquor and material submerged therein, the action of said streams of liquor will cause 65 said liquor to be circulated spirally therein

and insure its contact with every part of said material thus producing a uniform color throughout the entire mass of wool or other material contained within the vat.

Above the head 40 and secured to the 70 branch pipe 25 is a deflector or hood 49 against which any liquor escaping upwardly from the upper end of the head 40 will strike and be deflected downwardly into the vat 12. 75

It is obvious that in case the head 40 rotates too rapidly the speed may be reduced by adjusting the members 42 so that the angle of the jets of liquor passing therefrom will be more nearly perpendicular to the upper surface 48 of the dye liquor within the vat 12.

By reducing the bore in the tubular members 45 relatively to the bores of the tubular members 42, means are provided whereby the jets of liquor forced downwardly through the perforations 47 in the tubular members 45 will have more force than the jets of liquor projected through the perforations 47 in the tubular members 42. 80 90

This apparatus is simple in construction, very effective in its operation and quickly produces a uniform color throughout wool or other material submerged in the liquor within the dye vat. 95

It is believed that with the foregoing explanation, the operation and many advantages of the invention will be fully understood without further description.

Having thus described my invention, I 100 claim:

1. The combination with a dye-vat having a perforated false bottom; a circulating pipe for the dye liquor having a branch extending downwardly into said vat; and a spraying device freely revoluble about the lower end of said branch pipe above the liquor and provided with means for ejecting jets downwardly onto said liquor and at an angle thereto. 105 110

2. The combination with a dye-vat having a perforated false bottom; a circulating pipe for the dye liquor having a branch extending downwardly into said vat; a head freely revoluble about the lower end of said branch pipe above the liquor; and a plurality of tubular members radiating from said head, closed at the outer ends and each having a series of lateral perforations between its closed end and said head inclined downwardly at an acute angle to the surface of said liquor. 115 120

3. The combination with a dye-vat having a perforated false bottom; a circulating pipe for the dye liquor having a branch extending downwardly into said vat; a head freely revoluble about the lower end of said branch pipe above the liquor; a plurality of tubular members radiating from said head, closed at the outer ends and each hav- 125 130

ing a series of downwardly extending perforations between its closed end and said head; and means whereby said tubular members may be adjusted about their axes 5 to cause jets of liquor to strike the upper surface of the contents of said vat at such angle as to effect a circulation of said contents about the axis of the vat.

4. The combination with a dye-vat having a perforated false bottom; a circulating pipe for the dye liquor having a branch extending downwardly into said vat; a head freely revoluble about the lower end of said branch pipe above the liquor; and a plurality 10 of tubular members radiating from said head, the bore of the outer portions of which are reduced in diameter and closed at their outer ends, said tubular members each having a series of downwardly extending 15 perforations between its head and its closed end adapted to eject jets against the upper surface of the liquor and at an angle thereto thereby causing the contents of the vat to be circulated about the axis thereof.

20 5. The combination with a dye-vat having a perforated false bottom; a circulating pipe for the dye liquor having a branch extending downwardly into said vat; a flange on the lower end of said branch pipe; anti-friction members on said flange; a freely 25 revoluble head surrounding and resting on said anti-friction members; and a plurality of perforated tubular members radiating from said head disposed above the liquor 30 and provided with a plurality of downwardly extending perforations adapted to eject jets onto the upper surface of the liquor and at an acute angle thereto.

6. The combination with a dye-vat having 35 a perforated false bottom; a circulating pipe for the dye liquor having a branch extending downwardly into said vat; a spraying device revolubly mounted on the lower end of said branch pipe above the liquor and 40 adapted to eject jets onto the upper surface of the liquor at an acute angle thereto; and means for lifting said spraying device from said vat.

7. The combination with a dye-vat having

a perforated false bottom; a circulating pipe 50 for the dye liquor extending from the bottom of said vat; a joint at the upper end of the main vertical portion of said pipe adapted to be swung about a horizontal axis; a horizontal pipe leading from said swing 55 joint and having a branch extending downwardly into said vat; a spraying device on the lower end of said branch pipe above the liquor and provided with a plurality of 60 downwardly extending perforations adapted to eject jets onto the upper surface of the liquor at an angle thereto; and means for moving said horizontal pipe about the axis of said swing joint to lift the spraying device from said vat. 65

8. The combination with a dye-vat having a perforated false bottom; a circulating pipe for the dye liquor having a branch extending downwardly into said vat; a spraying device revolubly mounted on the lower 70 end of said branch pipe above the liquor and provided with a plurality of downwardly extending perforations adapted to eject jets onto the upper surface of the liquor at an angle thereto; a centrifugal pump in said 75 circulating pipe; and a steam turbine mounted directly on the shaft of said pump.

9. The combination with a dye-vat having a perforated false bottom; a circulating system for the dye-liquor consisting in part 80 of a pipe extending from the bottom of the vat; a pump, and a downwardly extending pipe terminating above the contents of said vat; and freely revoluble mechanism mounted on the lower end of said downwardly 85 extending pipe and adapted to eject a plurality of jets of liquor upon the upper surface of the contents of the vat with such force and at such angle as to cause said contents to be circulated in the vat and said 90 spraying device to be rotated about the axis of the downwardly extending pipe.

Signed by me at 746-7 Old South Bldg., Boston, Mass., this 26th day of April, 1920.

CHARLES H. ROBBINS.
